D 13,389

EX

No. 13,389

Oct 31, 1882

UNITED STATES PATENT OFFICE.

JOHN L. POPE, OF CLEVELAND, OHIO.

DESIGN FOR A WHIFFLETREE-PLATE.

SPECIFICATION forming part of Design No. 13,389, dated October 31, 1882.

Application filed August 2, 1882. Term of patent 7 years.

To all whom it may concern:

Be it known that I, JOHN L. POPE, of Cleveland, in the county of Cuyahoga and State of Ohio, have invented and produced a new and original Design for Whiffletree-Plates, of which the following is a specification, reference being had to the accompanying engraving, forming part thereof.

My invention relates to a design for whiffletree-plates; and it consists in the shape shown and described in the engraving accompanying this specification.

At *a* the plate is cast or otherwise made with the usual bolt or swivel hole, at which pivotal connection of the trees with the thills or shaft is had. Surrounding this hole is a raised tapering circular portion, *b*, and in line with the central hole, *a*, are four other countersunk holes at *c c c c* to permit the attachment of the plate

by screws, as usual. The edges of the plate are similar in form, and a description of one edge will therefore suffice. At about the middle of the edge of the plate there is an outward curve, *d*, whose extremities run into oppositely-disposed curves *e e*, and these terminate in points or projections *i*, from which latter extend other inward curves *m*, of greater length, that meet the semicircular ends *n* of the plate proper, all as plainly seen in the engraving.

I claim as my new design—

A whiffletree-plate having substantially the shown and described configuration.

In witness whereof I hereunto set my hand this 22d day of June, 1882.

JOHN L. POPE.

In presence of—

CHAS. W. MOSES,
C. M. COPP.
